(57) **CLAIM**

The ornamental design for a vacuum cleaner head, as shown and described.

DESCRIPTION

FIG. 1 is a top, front perspective view of a first embodiment of a vacuum cleaner head, illustrating our new design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof;

(Continued)

FIG. 8 is a top, front perspective view of a second embodiment of a vacuum cleaner head, illustrating our new design; FIG. 9 is a front view thereof; FIG. 10 is a rear view thereof; FIG. 11 is a left side view thereof; FIG. 12 is a right side view thereof; FIG. 13 is a top view thereof; and, FIG. 14 is a bottom view thereof. The broken lines illustrate portions of the vacuum cleaner head that form no part of the claimed design.
